TOOTHBRUSH HOLDER

Filed May 14, 1927

FIG. 1.

FIG. 2.

Edward Fromwiller,
INVENTOR
BY Victor J. Evans
ATTORNEY

UNITED STATES PATENT OFFICE.

EDWARD FROMWILLER, OF BROOKLYN, NEW YORK.

TOOTHBRUSH HOLDER.

Application filed May 14, 1927. Serial No. 191,450.

My present invention has reference to a bath room appliance, and is in the nature of a combined tooth brush, tooth paste tube and tumbler holder.

- 5 An object is the provision of an article for this purpose, which, while of a simple construction, is of an ornamental nature and which will add to the attractiveness of the place in which it is positioned, and further
 10 wherein the heads or bristle ends of the tooth brush supported on the device are received in domes which are preferably transparent so that the bristles will be protected from dirt and dust as well as from microbes.
 15 A further object is the provision of an article for this purpose which is preferably wholly formed of pressed metal to include a body portion which is in the nature of a shelf or plate, formed with an ornamental
 20 upstanding back and sides, as well as a depending apron at the front thereof which merges into a bead or ledge, the said plate, at points throughout the length thereof being formed with semi-circular flanges and
 25 the inner walls provided by the openings are notches for the reception of the neck portions of tooth brushes, the flanges having screwed therein inverted cup or dome members which fully enclose the bristle
 30 heads of the brushes, the device being also provided with a holder for a glass and with a depending comparatively wide hook-shaped member that affords a support for a tube of tooth paste.
 35 The drawings illustrate a satisfactory embodiment of the improvement.

In the drawings:

Figure 1 is a perspective view thereof.

Figure 2 is a sectional view approximately
 40 on the line 2—2 of Figure 1.

The improvement is preferably of metal and may be stamped or otherwise shaped to provide the same with a straight plate or shelf 1. The plate 1 has its ends rounded, and formed with upstanding side flanges 2 and with spaced back flanges 3. The back flanges are provided by gracefully curving these portions of the device and these flanges are reinforced by grooving the same from the outer face thereof to afford inwardly extending beads 4. The front of the plate 1, at the center thereof, is extended outwardly to afford the same with a rounded portion and the said front including the rounded portion thereof is beaded to form

the same with an upstanding ledge and with a depending flange or skirt 5. The mentioned rounded portion at the center of the plate or shelf has preferably fixed therein an annulus or like ring member 6. The annulus may be integrally formed with the plate and has secured thereon and extended upwardly therefrom an ornamented annular portion 7 that affords a holder for a glass or tumbler. The upper edge of the tumbler 65 support 7 is beaded and the body thereof is preferably cut away to form the same with leg portions 8 whose outer edges are rounded away from each other, and the said legs may be and preferably are provided with openings of ornamental designs.

Between the back portions 3 and the body plate or shelf 1 there are integrally formed reinforcing ribs 9 and above these ribs the back portions are provided with openings 75 10 for the reception of means whereby the device may be attached to a vertical support.

Below the tumbler holder the back of the plate 1 is extended downwardly and from 80 thence rounded upwardly to form the same with a comparatively wide hook-like portion 11 that affords a support for a tube 12 for a tooth paste.

The plate 1, to the opposite sides of the 85 tumbler holder 7, has equidistantly spaced semi-circular openings 13 therethrough, and the inner straight walls of these openings has substantially key-hole notches 14 therein. The portions of the plate provided with 90 the openings 13 and notches 14 are preferably depressed from the plate, the said depressed portions providing annular flanges 15 which project a slight but suitable distance above the face of the plate 1, thus 95 forming the plate with annular ribs that add to the ornamentality thereof. The flanges 15 have their inner portions preferably threaded, and screwed in these flanges 15 there are inverted cup or dome-shaped members 17. The members 17 are preferably of 100 glass or other transparent material, and the said members are designed to serve as protectors for the bristle heads of the tooth brushes 18 when the latter are inserted 105 through the openings 13 and the neck portions thereof are brought into the notches 14. My improvement provides a sanitary protector for the tooth brush as well as a separate compartment for the several tooth 110

brushes. The tooth brushes may be readily inserted and effectively supported on the improvement. The protector cups or domes 17 prevent dust or dirt contacting with the 5 bristle heads of the brushes and, of course, prevent the spreading of germs from one to another brush. The device while of a simple construction is of highly ornamental nature and the many advantages thereof will, it is 10 thought, be apparent and appreciated by those skilled in the art to which such invention relates without further detailed description.

While I have stated that my improvement 15 is preferably formed of pressed metal, I do not wish to be limited to the employment of this particular material, as I may find it desirable to mould the same of porcelain or

to construct the improvement of other materials.

Having described the invention, I claim:—

In an article of the class described, a plate having upstanding flanges on the sides and end thereof and a depending front flange, 20 said plate and flanges having reinforcing 25 beads, said plate having an annular depressed portion, the lower wall of which being provided with a semi-circular opening and the straight wall formed by the opening having a key-hole notch and an inverted 30 transparent dome screwed in the upstanding flanges and surrounding the semi-circular opening and notch.

In testimony whereof I affix my signature.

EDWARD FROMWILLER.
